UNITED STATES PATENT OFFICE.

FRANK M. CHANDLER, OF OTTAWA, WEST VIRGINIA, ASSIGNOR OF ONE-FOURTH TO
J. FLOYD MEADOWS AND ONE-FOURTH TO KIE ANDERSON, BOTH OF OTTAWA,
WEST VIRGINIA.

END GATE.

Application filed June 10, 1925. Serial No. 36,234.

To all whom it may concern:

Be it known that I, FRANK M. CHANDLER, a citizen of the United States, residing at Ottawa, in the county of Boone and State 5 of West Virginia, have invented new and useful Improvements in End Gates, of which the following is a specification.

This invention relates to end gates and has particular application to a novel construction and means for effectively holding the gate in closed position to prevent rattling, and also allow the gate to be quickly and conveniently opened as the occasion may 10 require.

15 The nature and advantages of the invention will be better understood when the following detailed description is read in connection with the accompanying drawing, the invention residing in the construction, combination and arrangement of parts as claimed.

In the drawing:

Figure 1 is an end elevation of a wagon showing by full lines the active position of 20 a gate holding means, the inactive position thereof being indicated by dotted lines.

Figure 2 is a fragmentary side elevation of the wagon.

Figure 3 is an enlarged fragmentary sectional view showing the gate in its closed 30 position.

Figure 4 is a sectional view on line 4—4 of Figure 1.

Figure 5 is a fragmentary perspective 35 view of the operating lever and locking bars.

Referring to the drawing in detail, A indicates generally a portion of a wagon, the end gate for which is indicated at B. This gate is pivoted as at 10 and is supported in 40 its lower horizontal position by means of chains or other flexible elements 11. Projecting rearwardly from the sides of the wagon body are spaced keepers in the nature of bracket plates 12, each of which has an 45 opening 13 to receive the adjacent link of the chain 11 and also provided with an opening 14 to receive the adjacent locking bar 15 when the gate is closed. The other end of each chain is secured to a perforated

plate 16 attached to the upper end of the 50 gate, as clearly shown in Figure 2.

The locking bars 15 above referred to are arranged to slide transversely across the end gate B through suitable guides 16, the corresponding inner extremities of these bars 55 being received by the bifurcated extremities of the cross head 17 of a substantially T-shaped lever 18 pivoted centrally upon the end gate, as at 19. As a matter of fact, this lever is pivoted upon the offset extremity 60 20 of an arm 21 which is secured to the end gate, and which offset extremity constitutes a stop to limit the movements of the lever 18, as will be readily understood. Manifestly, when the lever is in a true vertical position shown by full lines in Figure 1, the locking bars are moved outwardly and arranged in end to end relation, in which position the bars 15 pass through the openings 14 of their respective keepers, thereby 65 effectively holding the gate in a closed position and in a manner to prevent rattling thereof. When the lever 18 is swung to the dotted line position indicated in Figure 1, the bars 15 are moved inwardly, or, in other 70 words, retracted from the keepers 12, so that the gate can be conveniently lowered to its opened position. In order to prevent movement of the lever 18, when the gate is closed, I employ a leaf spring 22 which is arranged 75 transversely across the gate to which it is secured, and which spring is formed with a bulged portion 22' which is adapted to receive and engage the lever 18 in the manner clearly shown in Figure 4.

80 While it is believed that from the foregoing description the nature and advantages of the invention will be readily apparent, I desire to have it understood that I do not limit myself to what is herein shown and 85 described, and that such changes may be resorted to when desired as fall within the scope of what is claimed.

Having thus described the invention, what 90 is claimed as new, is:—

The combination with a wagon body having a pivoted end gate, of a bracket arm 95 secured to said gate and having an angular

shaped extremity, a vertically disposed lever pivoted on said extremity, said lever including a cross head, apertured keepers projecting from the sides of the wagon body 5 beyond the gate, locking bars having their adjacent ends pivotally connected with said cross head and adapted to be simultaneously moved into and out of engagement with their

respective keepers, said cross head cooperating with said bracket to limit the swinging movement of said lever, and a resilient element arranged transversely of the gate and adapted to engage said lever to hold the latter immovable when the gate is closed. 10

In testimony whereof I affix my signature.
FRANK M. CHANDLER.
